US00D845141S

(12) United States Design Patent (10) Patent No.: US D845,141 S
(45) Date of Patent:  Apr. 9, 2019

(54) PACKAGE WITH SURFACE ORNAMENTATION

(71) Applicant: Société des Produits Nestlé S.A., Vevey (CH)

(72) Inventor: Béatrice Mariotti, Suresnes (FR)

(73) Assignee: Société des Produits Nestlé S.A., Vevey (CH)

() Term: 15 Years

(21) Appl. No.: 29/630,550

(22) Filed: Dec. 21, 2017

(30) Foreign Application Priority Data

Jun. 22, 2017 (CH) 143298

(51) LOC (11) Cl. 09-01

(52) U.S. Cl.

USPC D9/643; D9/434

(58) Field of Classification Search

USPC D3/270, 271.1-271.4; D7/510, 514-520,

D7/599, 604, 613, 619.2, 623, 628;

D9/600, 643-647, 652, 414-418,

D9/430-434; 206/457, 459.5, 527;

215/381-384, 400; D20/23

CPC B65D 5/42; B65D 5/4258; B65D 81/60;

B65D 81/365; B65D 81/366; B65D

81/368; B65D 2203/00; B65D 2203/02;

B65D 37/00; B65D 77/00; A63H 33/16

(57) CLAIM

The ornamental design for a package with surface ornamentation, as shown and described.

DESCRIPTION

The sole FIGURE is a front elevation view of a package with surface ornamentation showing my new design.

The dash-dash broken lines define the boundary of the claimed design and form no part of the claimed design.

1 Claim, 1 Drawing Sheet
